THROTTLE CONTROL DEVICE

Erold F. Pierce, Pines Lake, N. J., assignor to
Wright Aeronautical Corporation, a corporation
of New York

Application July 15, 1941, Serial No. 402,455

4 Claims. (Cl. 123—103)

This invention relates to controls for internal combustion engines and is particularly concerned with a device adapted to govern an engine to constant power output by causing the engine throttle to be responsive in its position to the liquid fuel flow of the engine.

Although the invention is applicable to internal combustion engines in general, it is particularly applicable to aircraft engines and the showing in the drawing includes the device as applied to a radial cylinder air-cooled aircraft engine. Various attempts have been made to control engine power automatically by maintaining constant manifold pressure but such constant pressure is not necessarily a true criterion for holding power constant unless engine R. P. M. is constant and unless controls are imposed in the system to compensate for temperature, atmospheric pressure, and exhaust back pressure variations. Accordingly, it is an object of this invention to control engine power by maintaining constant the amount of liquid fuel fed to the engine carburetor or to any other fuel-air proportioning device which may be used. A further object of the invention is to make the engine throttle sensitive to variations in liquid fuel flow to the engine and further, to provide adjustable means by which the amount of fuel flow to the engine may be regulated, thus setting the engine for different power outputs.

Further objects of the invention will become apparent in reading the annexed detailed description in connection with the drawing, in which:

Fig. 1 is a section through the control device of the invention, with auxiliary apparatus indicated diagrammatically; and

Fig. 2 is a side elevation of an engine with the control apparatus installed thereon.

Referring first to Fig. 2, I show an aircraft type engine comprising a crankcase 10 containing a crankshaft 11 whose front end comprises a propeller shaft 12 and whose rear end drives a supercharger impeller 13, the latter being supplied with a fuel-air mixture from a carburetor 14 and delivering its compressed charge through an intake manifold 15 to an engine cylinder 16. The carburetor 14 is provided with the usual throttle having a throttle lever 17 connected through a link 18 with a servomotor 19. At the bottom of the servomotor 19 is a manual throttle adjusting piston 20 connected through a bell-crank 21 and an operating rod 22 to the usual pilot's throttle quadrant, not shown. The servomotor 19 is energized by a control unit 24 secured to the rear of the engine through a Venturi member 25 through which liquid fuel passes from a feed line 26 to a pipe 27 delivering to the carburetor 14. The devices 19, 24 and 25 are shown in larger scale in Fig. 1. It may be here noted that the servomotor 19 is of a type similar to

that disclosed in my co-pending application entitled "Hydraulic throttle control," bearing Serial No. 293,207, and filed September 2, 1939. The servomotor, briefly, comprises a cylinder 30 in which a piston 31 is slidable, said piston being directly connected through a piston rod 32 to the link 18. A lower piston 34 is disposed in the cylinder 30, this being connected to the manual throttle rod 20 which rod, within the cylinder 30 housing, comprises a shut off valve at 35 for hydraulic fluid lines 36 and 37 leading respectively to ports in the cylinder wall above and below the piston 34. The piston 34 is further provided with a check valve 38 and the cylinder wall is provided with a bypass 40 connecting the top and bottom of the cylinder but masked at its lower end by the piston 34 when the latter is in its lowermost position. When the piston rod 20 is in its bottom position, the piston 31 is moved up and down by admission of hydraulic fluid through one or the other of the passages 36 or 37. If manual throttle operation is desired, the piston 34 is moved up until it abuts the bottom of the piston 31, liquid between the pistons evacuating through a check valve 38 whereupon the two pistons are locked together hydraulically for manual throttle control until such time as the piston 34 is moved to its lowest position whereupon automatic throttle operation may again take place.

The Venturi housing 25 includes a Venturi throat 42 which is connected through a conduit 43 to a cavity 44 defined in a chamber 45 by a yielding diaphragm 46 and a rigid partition 47, the latter two elements being sealed to the walls of the chamber. Venturi static pressure is led from the large bore of the venturi through a conduit 43 to a cavity 49 in the chamber 45 defined by the partition 47 and by a yielding diaphragm 50 secured to the walls of the chamber. Venturi static pressure is balanced by a spring 51 in a cavity 52 below the cavity 49, the pressure in said cavity 52 being substantially atmospheric. This atmospheric pressure is conducted through a conduit 53 to a cavity 54 defined between the upper wall of the diaphragm 36 and the lower wall of a yielding diaphragm 55. The latter defines with the top of the chamber 45 a cavity 56 which is subjected to less than atmospheric pressure by a vacuum pump 57 communicating, through an orifice 58, with said cavity 56 through a pipe 60. Branching from the pipe 60 is a gauge 61 and a vacuum relief valve assembly 62, the latter comprising a valve 63 loaded by a spring 64 whose compression may be adjusted by a control 65 available to the pilot. By the use of the control 65 the pilot may preset any desired vacuum on the gauge 61 which latter may be calibrated in power units or with any appropriate indicia.

The several diaphragms 55, 46 and 50 are connected together by a stem 66 whose lower end comprises a servo valve 67 slideable in a bore 68. Pressure oil is directed to a port 69 in this bore from an engine oil pressure line 70 shown in Fig. 2 which is connected into the normal pressure lubricating system of the engine. The bore 68 is further provided with scavenge ports 70 communicating with a pipe 71 leading to the engine oil sump. The bore 68 is further provided with oil ports 73 and 74 connected respectively with the servomotor conduits 36 and 37.

The valve 67 and the associated ports are so arranged that when the valve is in a central position, the ports 73 and 74 are closed, holding the servomotor 19 stationary. If the valve 67 is raised, pressure oil passes from the port 69 to the port 73, thereby directing pressure oil to the bottom of the throttle operating piston 31 to cause opening of the engine throttle 17. Oil passing from above the piston 31 is carried to the engine sump through the ports 74 and 70. If the valve stem 67 is lowered, pressure oil passes from the port 67 to the port 74 thus closing the engine throttle, while scavenged oil passes from below the piston 31 through the port 73 to the drain port 70. Although the stem 66 passes through an opening in the partition 41, a fairly close fit is naturally provided so that the leakage path from chamber 49 to chamber 44 around the stem 66 is restricted as compared to the size of passageways 43 and 48. Accordingly, the pressures in chambers 44 and 49 are proportional to the Venturi suction and Venturi barrel pressures respectively.

Referring now to the diaphragm and Venturi operation, it will be seen that Venturi static pressure is balanced by the spring 51, and that a balance obtains between the cavity 44 connected with the Venturi throat and the calibrated low pressure existing in the cavity 56, so long as the valve 67 is neutral. Should the flow of fuel to the engine increase, there will be a lower pressure at the Venturi throat which is transmitted to the cavity 44, thereby unbalancing the diaphragm system and lowering the valve 67 to cause closure of the engine throttle. Engine throttle closure of course will decrease the demand for liquid fuel and when the liquid fuel flow diminishes through the venturi to the necessary extent, the engine throttle will stabilize in a new position. Should the flow of fuel through the venturi decrease for any reason, the increased pressure in the cavity 44 resulting from such decrease will raise the valve 67 thereby opening the throttle 17 through the operation of the servomotor to increase the fuel demand.

When it is desired to alter engine power, change in degree of vacuum in the cavity 56 will cause unbalance in pressure between the cavities 56 and 44 and throttle opening or closing will follow in the same manner as described above. Although an adjustable vacuum regulating system is shown as being a convenient and practical one, any other sort of yieldable adjustment could be utilized, such as a spring, or a pneumatic or hydraulic pressure system.

Since the amount of liquid fuel consumed by the engine is a reasonably true criterion of engine power, assuming that the carburetor properly proportions the liquid fuel and air, it will be readily appreciated that the reading of the gauge 61 will be a proper indication of power output and furthermore, that the adjusting knob 65 will be an adequate means to preset any desired engine power.

Under some conditions of operation, automatic power regulation may not be desired in which case the pilot may take the control of the engine away from the devices 24 and 25 by manipulating the manual throttle rather than by manipulating the adjustment knob 65.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. Constant power control means for an internal combustion engine including a carburetor having a throttle comprising a venturi in a liquid fuel feed line to the carburetor, a diaphragm system responsive to the Venturi pressure drop, controllable elastic means to adjust the balance point of the diaphragm system, and means responsive to diaphragm movement to adjust the carburetor throttle in an opening direction in response to a decrease of said Venturi pressure drop and in a closing direction in response to an increase of said Venturi pressure drop.

2. In a power control for an internal combustion engine including a throttle and a fuel supply line, a venturi in said line, a housing including a chamber therein, a partition across said chamber, yielding diaphragms in the chamber on opposite sides of said partition and defining therewith two cavities, means connecting one cavity with the Venturi throat, means connecting the other cavity with the Venturi barrel, a stem connecting said diaphragms, a servo valve operatively connected to said stem, manually adjustable elastic means opposing the Venturi forces imposed on said diaphragms, and a motor actuated by servo valve movements operatively connected to the engine throttle.

3. In a power control for an internal combustion engine including a fuel-air proportioning mechanism, a fuel feed line to the mechanism including a venturi, a chamber having partitions dividing same into a plurality of cavities of said partitions being movable jointly, conduits from the venturi to certain of said cavities, means to maintain in another of said cavities a uniform pressure tending to counteract the Venturi pressure, unbalance between the uniform and Venturi pressures causing movement of said jointly movable partitions, an engine air throttle, means actuated by changes in position of said jointly movable partitions to alter the setting of said throttle, and means to adjust said uniform pressure.

4. In a power control system for an internal combustion engine, a carburetor having a throttle and a fuel feed line, a venturi in said feed line, a housing including a chamber therein, a partition across said chamber, yielding diaphragms in the chamber on opposite sides of said partition and defining therewith two cavities, means connecting one cavity with the Venturi throat, means connecting the other cavity with the Venturi barrel, a stem connecting said diaphragms, a servo valve operatively connected to said stem, a motor actuated by servo valve movements operatively connected to said throttle, and elastic means opposing the Venturi forces imposed on said diaphragms, said elastic means including an adjustable source of fluid pressure.
